(No Model.)

W. JOHNSTON.
HOLDER FOR PILLOW SHAMS.

No. 450,075.

Patented Apr. 7, 1891.

UNITED STATES PATENT OFFICE.

WILLIAM JOHNSTON, OF MENOMINEE, MICHIGAN, ASSIGNOR OF ONE-HALF
TO ABRAM W. MARLATT, OF MARINETTE, WISCONSIN.

HOLDER FOR PILLOW-SHAMS.

SPECIFICATION forming part of Letters Patent No. 450,075, dated April 7, 1891.

Application filed September 11, 1890. Serial No. 364,681. (No model.)

To all whom it may concern:

Be it known that I, WILLIAM JOHNSTON, a citizen of Menominee, in the county of Menominee and State of Michigan, have invented certain new and useful Improvements in Holders for Pillow-Shams; and I do hereby declare the following to be a full, clear, and exact description of the invention, such as will enable others skilled in the art to which it appertains to make and use the same.

My invention relates to an improvement in holders for pillow-shams, and has for its object to produce a device for the purpose stated which shall be very simple in construction, cheap to manufacture, and effective in the performance of its function.

A further object is to so construct the device that it may readily be thrown from the pillows and against the upper portion of the head of the bed, and at the same time hold the shams in proper position when lowered upon the pillows.

A further object is to construct the device in such manner that the entire frame, springs, &c., will be out of sight.

With these objects in view the invention consists in certain novel features of construction and combinations and arrangements of parts, as hereinafter set forth, and pointed out in the claims.

In the accompanying drawings, Figure 1 is a view showing my improvements attached to the head-board of a bed, with the frame in its normal position. Fig. 2 is a view of the device, showing the frame thrown up. Fig. 3 is a detached view of the crank-shaft.

A represents the head-board of a bed, to which a thin strip of wood *a* is secured and made to extend from side to side thereof. Secured to the center of this strip and projecting forwardly from it is a bar *b*, preferably of wood, having a recess *c* at its center, said bar being braced by means of a series of blocks *d*, two of which are located at the ends of the bar and two at the center at opposite sides of the recess *c*. Secured to and projecting downwardly from the central blocks *d* is a bracket *e*, preferably of wire, for the reception of the lower ends of two or more coiled springs *f*, or, if desired, one large coiled spring. The upper ends of the springs *f* are connected to the crank-arm *g* of a shaft *h*, mounted on the bar *b*. The free ends of the shaft are bent at right angles to produce

arms *i*, having lateral projections *j* at their ends. Pivotedly connected to the laterally-projecting portions *j* is a frame *B*, consisting of two parallel strips 1 1, parallel cross-bars 2 2, connecting said strips at points between their ends, and diagonal cross-bars 3 3 at the ends of the frame, all of which parts are preferably made of light strips of wood. Secured to the upper strip 1 is a piece of tape 4, to which the pillow-sham may be pinned. With the device thus constructed the pillow-shams may be held in proper position. They may be thrown up against the head-board of the bed, and when in use the entire device is hid from view.

Having fully described my invention, what I claim as new, and desire to secure by Letters Patent, is—

1. The combination, with a strip and a frame, of a crank-shaft pivotally connected with the strip and the frame, and spring or springs connecting an arm on the shaft with the strip, substantially as set forth.

2. The combination, with a strip, of a cross-bar secured thereto and having a recess at its center, a crank-shaft mounted on said bar, a bracket projecting downwardly from the bar, springs connecting the crank-shaft and bracket, arms at the ends of said shaft, and a frame carried by said arms, substantially as set forth.

3. In a pillow-sham holder, the combination, with a strip, of a bar secured thereto, a crank-shaft mounted on said bar, a bracket projecting from said bar, springs connecting the crank-shaft with said bracket, arms on said shaft, a frame carried by said arms, and a tape secured to one edge of said frame, substantially as set forth.

4. In a pillow-sham holder, the combination, with a strip, of a crank-shaft having its crank located at the center of said strip, arms projecting from said shaft, a frame carried by said arms, a bracket secured to said strip, and springs connecting said bracket with the crank-shaft at the center of said strip, substantially as set forth.

In testimony whereof I have signed this specification in the presence of two subscribing witnesses.

WILLIAM JOHNSTON.

Witnesses:

AMOS HOLGATE,
LOUISE ALLEN.
